UNITED STATES PATENT OFFICE.

HORACE B. TRAVER, OF CHICAGO, ILLINOIS, ASSIGNOR TO W. C. RITCHIE & COMPANY, OF CHICAGO, ILLINOIS, A CORPORATION OF ILLINOIS.

PASTEBOARD-BOX-NECKING MACHINE.

1,096,075.

Specification of Letters Patent.

Patented May 12, 1914.

Application filed February 15, 1912. Serial No. 677,801.

To all whom it may concern:

Be it known that I, HORACE B. TRAVER, a citizen of the United States, residing at Chicago, in the county of Cook and State 5 of Illinois, have invented certain new and useful Improvements in Pasteboard-Box-Necking Machines, of which the following is a specification.

My invention relates to the art of making pasteboard boxes, and more particularly to means for securing the necks of such boxes to box-bottoms or tops.

My invention is particularly adapted to the necking of cigarette-boxes and the like, 15 and will be described in connection with such use, although it is not limited thereto. In order that this application of my invention and the use of the terms herein may be best understood, it may be explained that 20 cigarette-boxes and the like comprise a top and a bottom, each of which consists of a rectangular piece of cardboard having sides and ends secured thereto, thus forming half a box, and usually termed simply a top or 25 a bottom, or a top-body and a bottom-body respectively. In order that these two parts constituting the box proper may be held in firm and alined position with respect to each other when the box is closed, a strip of cardboard, known as the box-neck, having its 30 ends secured together and of a height greater than that of the sides of the box-body (or top, as the case may be) and formed to fit nicely within the sides and 35 ends of the top and bottom body portions of the box, is secured to each box-bottom (or top, as the case may be) by glue or similar adhesive. The necking of such boxes by hand has proven very slow and costly, and 40 it is the principal object of the present invention to save much of the time, labor and expense heretofore attending this work.

A further important object is to improve the quality of such boxes, particularly with 45 respect to their appearance and strength.

A preferred arrangement and organization of mechanisms whereby these and other objects and advantages are attained is illustrated in the accompanying drawings forming 50 a part of this specification, in which:

Figure 1 is a broken side elevation of a box-necking machine embodying this invention, one of the lower guides being removed; Fig. 2 is a top plan of the machine illustrated in Fig. 1; Fig. 3 is an enlarged lon-

gitudinal section of the rear end of the machine taken on a medial line through the conveyer; Fig. 4 is a top plan view of the portion shown in Fig. 3; Fig. 5 is an enlarged transverse vertical section on the line 5—5 of Fig. 2; Fig. 6 is an enlarged fragmentary top plan of that portion of the machine containing the adhesive-applying disks and associated parts; Fig. 7 is an enlarged sectional view on the line 7—7 of Fig. 2; Fig. 8 is an enlarged horizontal fragmentary cross section showing a former passing downward between the ends of the ways and a box-neck and box-bottom pasted thereto being ejected from the former; Fig. 9 is an enlarged fragmentary plan view of means coöperating with the conveyer to rotate the formers, cover-plates being removed to show some of the parts; Fig. 10 is a perspective of a box-bottom-body, and Fig. 11 is an enlarged perspective of a box-neck adapted to fit into the box-bottom of Fig. 10.

The illustrated structure, stated briefly, comprises an endless chain traveling over sprockets and carrying a plurality of formers, each of which is adapted to receive the neck of a box and carry the sides of the same into contact with a pair of oppositely disposed adhesive-charged disks, the former being adapted to rotate a quarter revolution after passing said disks and thereby present to the adhesive coating action of a second pair of similar disks the ends of the box-neck on said former, after which adhesive-charging process, and a box-bottom being placed by hand upon a box-neck on one of said formers, the ends of the box-bottom are brought into sliding contact with spring-pressed jaws whereby the neck and the bottom are caused to unite securely together through the action of the adhesive; and thereupon the former is given another quarter revolution, bringing the sides of the box between similar jaws with a like result thereto. The gluing and pressing of the parts together being now completed, the box-neck and bottom secured thereto is forced off the former by engagement of the box-neck with ways eccentric to the line of travel of the former.

All of the operating mechanism is mounted in or upon a channeled frame 20, preferably made of cast-iron. This frame is supported by a secondary frame, which may well be made of wood, comprising a bot-

tom 21, end members 22 and 23 and side members 24, the latter constituting guides for the formers whereby the latter are prevented from rotation while passing from the rear of the machine to the front thereof and are caused to enter the ways of the channel 20 in the desired position.

The machine may be supported upon standards in any approved way.

10 *Driving mechanism.*—A driving shaft 25 carrying a sheave or pulley 26, by means of which power is transmitted to said shaft, is arranged to rotate in suitable bearings in the sides of the channel 20. A clutch 27 of ordinary construction is splined to said shaft and operated by means of a hand-lever 28 mounted upon the shaft 29 which is journaled in the bracket 29' secured to the frame 20, the shaft 29 carrying also the clutch-jaw 30, and providing means for starting and stopping the machine at will.

25 The driving shaft 25 carries a pinion 31 which meshes with a larger gear 32 mounted upon a shaft 33 rotating in suitable bearings in the sides of the channel frame 20. This shaft carries, on the opposite side of the frame 20, a small pinion 34, adapted to mesh with a larger gear 35 mounted upon the shaft 36, journaled in the walls of the frame 20. The intermeshing of these gears is best illustrated in Fig. 4. It will thus be seen that a high degree of speed, such as may be furnished to the sheave wheel 26 by an electric motor (not shown) is reduced to 35 a working speed at the shaft 36, which is the driving shaft for the conveyer and the adhesive-applying mechanism hereinafter to be described.

30 The shaft 36 carries a sprocket 37 between the walls of the channel 20. This sprocket engages and drives the endless conveyer chain 38, the chain being supported at the other end of the machine by a similar sprocket 39 on a shaft 40 slidably mounted in the frame 20 and longitudinally adjustable therein by means of the hand-nut 41 turning upon the threaded stem 42 secured to the sliding bearing member 43 and passing through an aperture in the end member 22. It is evident that by turning the hand-nut 41 the chain may be tightened or made slack for any purpose, such as dismounting the same or the repair of parts.

35 *The adhesive-applying mechanism.*—On the shaft 36 is secured a sprocket 44 adapted to drive an endless chain 45, which travels in a horizontal direction alongside the channel 20, and over a similar sprocket 46 (see Fig. 5) on a shaft 47 arranged to rotate in bearings in the channel 20. The shaft 47 carries a gear-wheel 48, which meshes with a similar gear 49 on the shaft 50, which shaft is also arranged to rotate in bearings in the walls of the channel 20. On either 60 side of the channel 20 on the shaft 50 is

mounted a bevel-gear 51 meshing with a similar gear 52 mounted upon a vertical shaft 53 rotating in a bearing bracket 54, which bracket also contains a bearing for the shaft 50. On the shaft 50 is secured a sprocket 55 carrying a chain 56 which transmits motion to a similar structure 57 on the shaft 58. Referring to Fig. 5, if we omit therefrom the shaft 47 and the parts mounted upon it, and also the gear 49, we will have 75 an exact reproduction of the mechanism mounted upon and associated with the shaft 58. It will not be necessary therefore to describe these parts again.

80 The purpose of the mechanism last described is to supply rotative motion to the adhesive-applying disks. The shaft 50 carries the oppositely disposed disks 59, and on the shaft 58 are mounted the like disks 59'. The shaft 53 has secured to it by means of the pin 53' the disk 60, while a similar vertical shaft 53' carries the disk 60'. The arrangement of these disks is such that the edges of the horizontal disks, as 60, are substantially in contact with the inner face of 85 the vertical disks, as 59, near the edge thereof. It is evident that upon rotation of the shaft 50 the disks 59 and 60 are rotated in the same direction at their point of contact.

85 Integral with the bracket 54 is formed a 95 basin or receptacle 61 adapted to hold glue or other liquid adhesive 62 of such quantity that the vertical disks, as 59, will have a portion thereof within the body of the adhesive. The basin 61 and bracket 54 are 100 made preferably of cast-iron, and integral therewith is preferably formed a boss 62' recessed to form a bearing for the shaft 50. A collar 63 pinned upon the shaft 50 prevents inward movement thereof. The basins 105 61 are further supported by means of transverse rods 64 rigidly secured in the frame 21 and passing through apertures in enlargements of the top edges of the basins respectively. Thumb-screws 65 hold the basins 110 adjustably and removably upon the rods 64.

115 It will be apparent that when the shafts 50 and 58 are rotated through the action of the chains 45 and 56 respectively all of the disks will be rotated and adhesive adhering to the vertical disks will be communicated to the edges of the horizontal disks. To prevent the application of an excessive amount of adhesive to these horizontal disks, scrapers 66 having a slot 67 adapted 120 to receive the vertical disks are provided. These are held in position upon lugs 68 integral with the basin 61 by thumb-screws 69.

125 *The conveyer mechanism.*—On the top surfaces of the channel-frame 20 are suitably secured, as by means of screws, the guides 70 and 71 respectively. The conveyer-chain 38 comprises a plurality of links of ordinary construction having a projecting hook 38' adapted to engage the next 130

succeeding link, and a plurality of former-carrying links interposed at suitable intervals between the ordinary links. These special carrier links comprise a link proper substantially like the ordinary links, but having rigidly and preferably integrally secured thereto a metallic cap or cover plate 72. The top of this cap or cover is at a sufficient distance from the plane of the link to enable the teeth of the sprocket to clear the same, as is well illustrated by dotted lines in Fig. 3. The top of this cover 72 is provided with a rigidly secured upstanding centrally arranged stud 73 adapted to hold a former 75 rotatably upon the cover or cap. As well shown in Fig. 6, the formers are held upon the stud by means of cotter pins 74.

The formers.—The formers 75 each comprise a rectangular body-portion or base having upstanding flanges 75^a and 75^b formed to receive the neck of the box, and carrying the same throughout the necking operation. The end flanges 75^b terminate in ledges or projections 75^c extending from the base of the former, and constituting rests for the box-neck thereon. The outside lengths of the flanges 75^a and 75^b are such that the box-neck will nicely fit thereon, and the height of these flanges is such that when a box-neck is resting upon the ledges 75^c its top edge will be substantially even with the top of said flanges.

The body-portion or base of the former is provided with a square extension 75^d, a portion of the corners of which is machined away immediately beneath the base forming a circular groove 75^e, which has a diameter just equal to that of the distance between opposite sides of the square portion 75^d. Projecting from the square portion 75^d and in opposite corners of said square portion are two studs carrying friction rollers 75^f. The distance between the sides of this square portion is such that this portion will slide smoothly yet without undue play between the guides 70 and 71.

The direction of travel of the conveyer and formers thereon is shown by the arrows in Fig. 1. It is of course understood that the box-necks are already formed at the time the necking process begins. Such a box-neck 76 in position on the former is well illustrated in Figs. 5 and 6.

The former rotating mechanism.—The adjustment of the parts is such that as a former containing a box-neck passes between the disks 60', the edges thereof contact with the opposite sides of the box-neck, and, as the disk edges are continuously coated with adhesive, it is evident that a quantity thereof will be communicated to the box-neck throughout the length of each side thereof, the adhesive being applied to the upper portion of the box-neck upon the

former, as well shown in Fig. 5. It is plain from the drawings that the disks 60' are adapted to apply adhesive to the sides of the box-neck, and the disks 60 to make such application to the ends thereof. To give the neck-containing formers the required quarter turn after they have passed the disks 60', a stop 77 is secured to one of the sides of the channel 20 adapted to engage one of the two friction rollers 75^f on each of the formers. The construction of this former rotating mechanism can be best understood by reference to Figs. 7 and 9, wherein are illustrated the same parts, but as applied to the opposite side of the channel 20, this illustration showing the mechanism for turning the formers at a later stage of their travel. The stop is indicated by 77'. The guides 70 and 71 are cut away as at 78' and 79' respectively to permit the natural movement of the corners of the square portion 75^d when the former is being drawn forward by the chain 38 yet held at one side by the stop 77'. The arrangement of the stop is such that when the former is given a quarter of a revolution the turning of the same draws the friction roller 75^f toward the central line of movement sufficiently to release the same from the stop 77', and thereupon the former again travels forward within the guides 70 and 71. The plates or covers 80, which are shown in Fig. 7, are removed in Fig. 9. These plates 80 secured upon the guides 70 and 71 engage the circular groove or recess 75^e; while the former is making its quarter revolution, and the former is thus held securely against lateral or vertical movement at such time. After passing the stop 77, the former having been given a quarter revolution thereby, the ends of the box-neck are presented to the disks 60 and similarly given an application of adhesive.

The compression or clamping means.—The box-neck is now ready for the application of a box-bottom 76', such as is illustrated in Fig. 10. An operator positioned at the side of the machine readily places such a box-bottom-body on each of the neck-containing formers as it emerges from between the disks 60, and thereupon the former carrying a combined bottom and neck passes between a pair of oppositely disposed clamps 81 (Fig. 4), held in position upon the guides 70 and 71 by means of screws 82, which are somewhat smaller in diameter than the apertures 83 in the clamps 81, thus allowing some movement of these clamping members 81. Spring-supporting brackets 84 are screwed to the sides of the channels 20, and a spring 85 seated within a recess in the clamp 81 provides compression whereby the ends of the box-neck and bottom-body are pressed firmly together as the former containing the same

passes between these clamps. The former is now given another quarter revolution by means of the stop 77' and the other mechanism already described, and passes between 5 the clamps 81' which press upon the sides of the box elements thereon. In this connection are mentioned the two top-guides 86 and 87 (see Fig. 1) secured by screws to the guides 70 and 71. The guide 86 is 10 adapted to hold the box-neck upon the former during the gluing operation, and the guide 87 has the function of holding the box-bottom and neck firmly upon the former and upon each other during the 15 clamping operation. The guide 87 may be conveniently held in position by screws 88 threaded into apertures 89 in the clamp-retaining studs 82.

The ejector and its operation.—Having 20 passed between the clamps 81', the box-bottom and neck are now found to be tightly secured together in the exact rectangular shape desired and with the opposite sides and ends and the top and bottom edges parallel, and 25 the completed work is ready to be taken from the machine. This is accomplished automatically by means of ways 90 which are circular in shape but eccentric with respect to the line of travel of the formers as they pass 30 over the sprocket 37. As well shown in Fig. 8, the sides of the formers fit closely between the two eccentric guides 90, and the box-neck 76 rests upon the top thereof. As the travel continues the former draws beneath 35 the top surface of the guides 90 and the box-neck is gradually forced off the former, and falls into any suitable receptacle, or may be carried away by a carrier and discharged at any suitable place. The form of conveyer 40 illustrated may be conveniently operated by a sprocket 91 on the shaft 36.

The operation of the machine has been well pointed out in the foregoing description of its parts. Two operators are sufficient, one to apply the necks to the formers, and one to place the box-bottoms thereon. It is evident that a large number of boxes may thus be necked in a very short time.

While there is herein illustrated and described preferred means for carrying the present improvements into effect, the invention is not limited thereto, as it will be obvious to those skilled in the art that many changes may be made in the form or details 55 of construction or arrangement of conveyer, driving mechanisms, formers, adhesive-applying devices, compression means and other features of the construction shown without departing from the spirit or scope of this 60 invention.

I claim:

1. In a box-necking machine, the combination of a traveling conveyer adapted to bodily transport the neck of a box, means 65 for applying an adhesive to the box neck on

said conveyer, and means for pressing together the box neck and the box bottom, substantially as described.

2. In a box-necking machine, the combination of a traveling conveyer adapted to 70 carry the neck of a box, means for operating said conveyer, means for applying an adhesive to a box-neck on said conveyer, and means for pressing together a box-neck and a box-bottom-body on said conveyer, substantially as described. 75

3. In a box-necking machine, the combination of a traveling conveyer adapted to 80 carry the neck of a box, means for operating said conveyer, means for applying an adhesive to a box-neck on said conveyer, means for pressing together a box-neck and a box-bottom-body on said conveyer, and means for ejecting a box-neck from said conveyer, substantially as described. 85

4. In a box-necking machine, the combination of a traveling conveyer adapted to 90 carry the neck of a box, means for operating said conveyer to transport the neck bodily, and means for alternately applying adhesive to the opposite sides and opposite ends of a box-neck on said conveyer, substantially as described.

5. In a box-necking machine, the combination of a conveyer adapted to carry the 95 neck of a box, means for operating said conveyer, means for alternately applying adhesive to the sides and ends of a box-neck on said conveyer, and means for alternately pressing together the sides and ends of a 100 box-neck and box-bottom-body on said conveyer, substantially as described. 100

6. In a box-necking machine, the combination of a conveyer adapted to carry the neck of a box, means for operating said conveyer, means for alternately applying adhesive to the sides and ends of a box-neck on said conveyer, means for alternately pressing together the sides and ends of a 110 box-neck and box-bottom-body on said conveyer, and means for ejecting a box-neck and bottom body from said conveyer, substantially as described. 110

7. In a box-necking machine, the combination of a traveling conveyer, means for operating said conveyer, a former carried by said conveyer and adapted to receive the neck of a box, means for applying an adhesive to a box-neck on said former, and means for pressing together a box-neck and box-bottom-body on said former, substantially as described. 115

8. In a box-necking machine, the combination of a traveling conveyer, means for operating said conveyer, a former transported bodily by said conveyer and adapted to receive the neck of a box, means for applying an adhesive to the exterior of a box-neck on said former, means for pressing together the coated neck and a box bottom 125

and means for removing the box-neck from said former, substantially as described.

9. In a box-necking machine, the combination of a traveling conveyer, means for operating the same, a former transported bodily by said conveyer and adapted to receive the neck of a box, and means for alternately applying adhesive to the sides and ends of a box-neck on said former, substantially as described.

10. In a box-necking machine, the combination of a conveyer, means for operating the same, a former carried by said conveyer and adapted to receive the neck of a box, means for alternately applying adhesive to the sides and ends of a box-neck on said former, and means for alternately pressing together the sides and ends of a box-neck and box-bottom-body on said former, substantially as described.

11. In a box-necking machine, the combination of a traveling conveyer, means for operating the same, a former transported bodily by said conveyer and adapted to receive the neck of a box, means for alternately applying adhesive to the opposite sides and opposite ends of a box-neck on said former, and means for ejecting a box-neck from said former, substantially as described.

12. In a box-necking machine, the combination of a traveling conveyer, means for operating the same, a rotatable former on said conveyer adapted to receive the neck of a box, means for rotating said former, and means for applying adhesive to the sides and ends of a box-neck on said former, substantially as described.

13. In a box-necking machine, the combination of a traveling conveyer, a rotatable former thereon adapted to receive the neck of a box, means for rotating said former, means for applying adhesive to the sides and ends of a box-neck on said former, and means for pressing together a box-neck and box-bottom-body on said conveyer, substantially as described.

14. In a box-necking machine, the combination of a traveling conveyer adapted to receive the neck of a box, means for applying adhesive simultaneously to the two sides of a box neck on said conveyer, said means comprising a pair of angularly disposed contacting disks arranged on each side of the conveyer, one of said disks of each pair substantially contacting with one side of a box-neck on said conveyer, and the other disk of each pair being in communication with a source of adhesive supply, substantially as described.

15. In a box-necking machine, the combination of an endless conveyer, a plurality of rotatable formers thereon, each adapted to receive the neck of a box, means for operating said conveyer and for rotating said

formers, means for applying adhesive alternately to the sides and ends respectively of each box-neck on said formers, and means for pressing together box-necks and box-bottom-bodies on said formers, substantially as described.

16. In a box-necking machine, the combination of an endless conveyer, a plurality of rotatable formers thereon, each adapted to receive the neck of a box, means for operating said conveyer and for rotating said formers, means for applying adhesive alternately to the sides and ends respectively of each box-neck on said formers, means for pressing together box-necks and box-bottom-bodies on said formers, and means for automatically ejecting a box-neck from said formers, substantially as described.

17. In a box-necking machine, the combination of a traveling conveyer, a rotatable former on said conveyer adapted to receive the neck of a box, means for operating said conveyer to bodily transport the former and for rotating said former at a point in its line of travel, means for preventing the rotation of said former at other points in its line of travel, and means for applying adhesive to the sides and ends of a box-neck on said former, substantially as described.

18. In a box-necking machine, the combination of a traveling conveyer, a rotatable former on said conveyer adapted to receive the neck of a box, means for operating said conveyer and for rotating said former at a point in its line of travel, means for preventing the rotation of said former at other points in its line of travel, means for applying adhesive to the sides and ends of a box-neck on said former, and means for pressing together a box-neck and a box-bottom on said former, substantially as described.

19. In a box-necking machine, the combination of a traveling conveyer, a rotatable former on said conveyer adapted to receive the neck of a box, means for operating said conveyer and for rotating said former at a point in its line of travel, means for preventing the rotation of said former at other points in its line of travel, means for applying adhesive to the sides and ends of a box-neck on said former, means for pressing together a box-neck and a box-bottom on said former, and means for automatically ejecting the box-neck and box-bottom from said former, substantially as described.

20. In a box-necking machine, the combination of an endless conveyer, a plurality of rotatable formers thereon, each adapted to receive the neck of a box, means for operating said conveyer, means for rotating said formers at points in their line of travel, means for preventing the rotation of said formers at other points in their line of travel, means for applying adhesive to the

sides and ends of each box-neck on said formers, and means for pressing together box-necks and box-bottoms on said formers, substantially as described.

5 21. In a box-necking machine, the combination of a conveyer, a form rotatably mounted on said conveyer and adapted to receive the neck of a pasteboard box, means for operating said conveyer, means to apply adhesive to the sides of the neck on said form during the travel of the conveyer, means to apply adhesive to the ends of the neck, means to cause said form and neck to rotate between said side and end adhesive-
10 applying means to bring the ends of the neck into the field of action of said means for applying the adhesive thereto, and means to prevent rotation of said form and neck during the application of the adhesive to the latter, substantially as described.

20 22. In a box-necking machine, the combination of a traveling conveyer belt, a series of formers carried thereby and adapted to support a neck, pasting devices disposed on opposite sides of the conveyer and arranged to apply paste to opposite sides of a neck carried therebetween upon a former, means to rotate the formers after the pasting of two sides of the neck to expose other sides to the action of subsequent devices, pressing devices disposed on opposite sides of the conveyer and arranged to compress therebetween two sides of a neck and superposed box to secure adherence, means to rotate the former after the compressing of two sides to expose other sides to the action of subsequent pressing devices, and means to strip the necked boxes from the formers, substantially as described.

40 23. In a box-necking machine, the combination of longitudinal spaced guides, a conveyer belt traveling therebetween, formers carried by the conveyer and adapted to support box necks, said formers provided with means to normally prevent rotation, paste applying devices arranged on opposite sides of the conveyer and adapted to apply paste simultaneously to opposite sides of a box neck on a former, means to partially rotate the former as it leaves the pasting devices, a second pair of paste applying devices similarly disposed and arranged to apply paste simultaneously to another two sides of the neck, means to compress opposite sides of superposed boxes against the corresponding sides of the box neck to secure adherence, other means arranged to press other sides of the box against corresponding sides of the box neck, and means to strip the necked boxes from the formers, substantially as described.

55 24. In a box-necking machine, the combination of longitudinal spaced guides, a conveyer belt traveling therebetween, formers carried by the conveyer and adapted to sup-

port box necks, said formers provided with means to normally prevent rotation, paste applying devices arranged on opposite sides of the conveyer and adapted to apply paste simultaneously to opposite sides of a box neck on a former, means to partially rotate the former as it leaves the pasting devices, a second pair of paste applying devices similarly disposed and arranged to apply paste simultaneously to another two sides of the neck, resiliently mounted plates disposed on opposite sides of the conveyer and arranged to simultaneously press two opposite sides of a superposed box against corresponding sides of the neck while on the former, means to further rotate the former, other similarly mounted plates arranged to act upon another two sides of the box and neck, and means to strip the necked boxes from the formers, substantially as described.

70 25. In a box necking machine, the combination of longitudinal spaced guides, an endless conveyer belt traveling therebetween, a series of formers carried by the conveyer and adapted to support box necks, the formers having a rectangular base fitting between the guides to normally prevent rotation, studs projecting from the formers, a pair of oppositely disposed paste applying devices arranged one on each side of the conveyer and adapted to apply paste simultaneously to opposite sides of the neck carried therebetween upon a former, a stop arranged to engage a stud and rotate the former one-quarter turn, a second pair of similarly disposed paste applying devices arranged to apply paste simultaneously to the other two sides of the neck, a pair of spring pressed plates disposed one on each side of the conveyer and arranged to simultaneously press upon two opposite sides of a superposed box and the corresponding sides of the neck while upon the former to secure adherence, a second stop to engage a stud to further rotate the former a quarter turn, a second pair of similarly mounted pressure plates arranged to act upon the other two sides of the box and neck, and means to strip the necked boxes from the formers, substantially as described.

75 26. In a box-necking machine, the combination of a traveling conveyer belt, a series of formers carried thereby and adapted to support a neck, pasting devices disposed on opposite sides of the conveyer and arranged to apply paste to opposite sides of a neck carried therebetween upon a former, means to rotate the formers after the pasting of two sides of the neck to expose other sides to the action of subsequent devices, pressing devices disposed on opposite sides of the conveyer and arranged to compress therebetween two sides of a neck and superposed box to secure adherence, means to rotate the former after the compressing of two

sides to expose other sides to the action of subsequent pressing devices, and means to strip the necked boxes from the formers comprising a cam plate arranged to engage 5 beneath the necked boxes and strip the same therefrom, substantially as described.

27. In a box-necking machine, the combination of longitudinal spaced guides, a conveyer belt traveling therebetween, formers 10 carried by the conveyer and adapted to support box necks, said formers provided with means to normally prevent rotation, paste applying devices arranged on opposite sides of the conveyer and adapted to apply paste 15 simultaneously to opposite sides of a box neck on a former, means to partially rotate the former as it leaves the pasting devices, a second pair of paste applying devices similarly disposed and arranged to apply paste 20 simultaneously to another two sides of the neck, resiliently mounted plates disposed on opposite sides of the conveyer and arranged to simultaneously press two opposite sides of a superposed box against corresponding sides of the neck while on the 25 former, means to further rotate the former, other similarly mounted plates arranged to act upon another two sides of the box and neck, and means to remove the necked boxes 30 from the formers comprising a cam plate arranged to engage beneath the necked boxes and strip the same therefrom, substantially as described.

28. In a box-necking machine, the combination of longitudinal spaced guides, an 35

endless conveyer belt traveling therebetween, a series of formers carried by the conveyer and adapted to support box necks, the formers having a rectangular base fitting between the guides to normally prevent 40 rotation, studs projecting from the formers, a pair of oppositely disposed paste applying devices arranged one on each side of the conveyer and adapted to apply paste simultaneously to opposite sides of the neck carried therebetween upon a former, a stop arranged to engage a stud and rotate the former one-quarter turn, a second pair of similarly disposed paste applying devices arranged to apply paste simultaneously to the 45 other two sides of the neck, a pair of spring pressed plates disposed one on each side of the conveyer and arranged to simultaneously press upon two opposite sides of a superposed box and the corresponding sides of the 50 neck while upon the former to secure adherence, a second stop to engage a stud to further rotate the former a quarter turn, a second pair of similarly mounted pressure plates arranged to act upon the other two 55 sides of the box and neck, and means to remove the necked boxes from the formers including a cam plate arranged to engage beneath the opposite edges of the necked boxes and strip the same therefrom, substantially as described.
